C. W. CANINE

LAUNDRY TAG

Filed April 6, 1927

Inventor.
Chester W. Canine.

by Orwig & Hague. Attorneys.

UNITED STATES PATENT OFFICE.

CHESTER W. CANINE, OF CINCINNATI, OHIO.

LAUNDRY TAG.

Application filed April 6, 1927. Serial No. 181,428.

My invention relates to that class of laundry tags in which there is provided a series of tags, each having a means for detachably connecting it to a garment, and each tag of 5 the series having a similar identification mark, and whereby after the garments bearing the tags have passed through a laundry operation, the tags having the similar identification marks may be assembled upon a 10 suitable assorting bar.

The object of my invention is to provide a tag of this class with means whereby it may be readily and quickly attached to a garment, and also readily and quickly removed 15 from a garment without danger of tearing or injuring the most delicate fabrics to which it may be attached.

More specifically it is my object to provide a tag of this class adapted to be connected 20 to a garment by a row of stitches formed on a sewing machine, and whereby all strains applied to the metal tag in a direction tending to separate it from the garment to which it is attached will be transmitted to a piece 25 of tape sewed by the same stitches to the opposite side of the garment, thus avoiding all tendency for such strains to tear or injure the garment to which the tag is applied.

Further in this connection it is my object 30 to so arrange the metal tag that the threads placed therein by the sewing machine will be protected from wear and possible breaking during the time the tag and the article to which it is attached are passed through 35 laundry operations.

My invention consists in the construction, arrangement and combination of the several parts of the tag, whereby the objects contemplated are attained, as hereinafter more 40 fully set forth, pointed out in my claims, and illustrated in the accompanying drawings, in which:

Figure 1 shows a face view of my improved tag attached to a garment as in use.

Figure 2 shows a similar view illustrating the opposite face of the tag.

Figure 3 shows a sectional view on the line 3-3 of Figure 1; and

Figure 4 shows an enlarged, detail, sectional view on the line 4-4 of Figure 3.

Referring to the accompanying drawings, it will be seen that the metal member of my improved tag is formed of a single piece of flat sheet metal, one end being substantially 55 rectangular in outline and the other end be-

ing tapered. The tag body portion is indicated generally by the reference numeral 10. Extended through the body portion 10 is a rectangular opening 11. Extended from a point adjacent to the opening 11 through the central portion of the tapered part of the metal tag is a series of round openings 12 extending through the tag, and in the face of the tag adjacent to one end of said openings there is formed a longitudinal groove 65 or depression 13, which extends down into the material of which the tag is formed to a distance approximately equal or greater than the thickness of the thread to be used in sewing, as will hereinafter more fully 70 appear. On one face of the tag there is an identification mark illustrated by the numeral 14 in Figure 2. The article to be marked is indicated by the numeral 15.

The tag comprises the metal plate 10 and 75 also a flexible member 16 preferably a length of tape.

The tag comprising the two members 10 and 16 is applied to a garment as follows: The metal tag member 10 is placed upon a 80 sewing machine with the face thereof that has the identification mark 14 on it uppermost, as shown in Figure 2. Then the garment to be marked is placed upon the metal tag member 10, and then the tape 16 is 85 placed upon the top of the garment. Then the sewing machine is operated in an ordinary manner and the needle first goes through the opening 12 nearest the opening 11, and then the needle consecutively passes 90 through the remaining openings 12 and makes one or more stitches in the garment 15 and the tag 16 beyond the lower end of the metal tag member 10. In Figure 4 the arrangement of these stitches is clearly illustrated, and they form what is commonly 95 known as a lock stitch.

When the sewing operation has been completed as described, the threads are cut off and the two tag members are firmly secured 100 to the garment on opposite sides thereof. By continuing the stitches beyond the metal tag member 10, as described, this end of the tag is held firmly in contact with the garment, and the longitudinally extended 105 thread, clearly shown in Figure 1, serves to prevent articles from catching under said end of the metal tag; and furthermore, by having some of the stitches pass through the fabric and flexible tag only, there is less 110

danger of the threads breaking at this point than though the stitches terminated within the openings in the metal tag member.

In practice I have demonstrated that tags

5 of this character sewed to garments in the manner described will pass through many laundry operations without the tags becoming detached or torn from the garment.

For the purpose of illustrating that my

10 improved tag will not injure the garment to which it is attached, I have substituted for a fabric garment, a sheet of thin paper and placed the two tag members on opposite sides thereof and connected them all together with a row of stitches as shown. I

15 have then grasped the upper end of the metal tag member in one hand and the adjacent end of the flexible tag member in the other hand and violently torn them apart,

20 which resulted in the threads all being cut at the points where they pass through the openings in the metal tag, and then these cut ends of the thread were removed through the paper and carried by the flexible tape, and upon careful examination of

25 the tissue paper thereafter it was found that the only openings therein were the ones made by the needle in sewing, and that the paper between these openings was not torn at any point, thus conclusively illustrating that no strains are applied to the garment itself by the use of my improved tag, even when the parts are violently torn apart.

Furthermore, and in the event that there 35 should be a direct pull in opposite directions upon the tag in one direction, and the garment to which it is attached in the other direction, then by reason of the fact that there is a comparatively large number of stitches, 40 the strains thus applied to the garment would be equally distributed over a wide area, and since the flexible tag is held firmly against the fabric by the stitches, a very great strain may be thus applied to the tag 45 and garment without injuring the garment.

By the use of the term "rigid" as applied to the tag member 10 in the accompanying claims, I do not desire to be understood as limiting my patent to the use of metal members only, but to such material as would not be readily penetrated by a sewing machine needle, and, therefore, would need to be formed with openings to receive the needle; and furthermore by the use of the term 55 "fabric" as applied to the tag member 16, I do not desire to be understood as limiting my invention to a tag member made of a woven material, but intend to cover a tag

member of this class which is capable of being readily penetrated by a sewing machine 60 needle.

I claim as my invention:

1. In a device of the class described, the combination of a flat rigid tag member adapted by means of its shape to be suspended from an assorting rod, and being formed with a row of openings to receive stitches, a second tag member formed of fabric and designed to be placed adjacent to one face of the rigid tag member with a garment between the two tag members, and a row of stitches extended through the openings in the rigid tag member through the garment and through the fabric tag member. 75

2. In a device of the class described, the combination of a flat rigid tag member adapted by means of its shape to be suspended from an assorting rod, and being formed with a row of openings to receive stitches, a second tag member formed of fabric and designed to be placed adjacent to one face of the rigid tag member with a garment between the two tag members, and a row of stitches extended through the openings in the rigid tag member through the garment and through the fabric tag member, one or more of said stitches being continued beyond the rigid tag member and being passed through only the fabric tag member and 90 the garment. 80

3. In a device of the class described, the combination of a flat rigid tag member formed with a row of openings to receive stitches, a second tag member formed of fabric and designed to be placed adjacent to one face of the rigid tag member with a garment between the two tag members, and a row of stitches extended through the openings in the rigid tag member through the 100 garment and through the fabric tag member. 95

4. In a tag of the character described, the combination of a rigid tag member having a series of openings formed in it, and a flexible tag member designed to be placed on opposite sides of a garment and designed to receive a row of stitches passed through the said openings, the garment and through the flexible member, said rigid tag member having a thread groove on one face extending between said openings, for the purposes stated. 105 110

Des Moines, Iowa, March 4, 1927.

CHESTER W. CANINE.
